UNITED STATES PATENT OFFICE.

RALPH W. DEIMLER, OF TOPEKA, KANSAS, ASSIGNOR OF ONE-HALF TO KENNETH L. PECK, OF TOPEKA, KANSAS.

SANITARY COVER FOR MILK CONTAINERS.

Application filed June 21, 1926. Serial No. 117,508.

My invention relates to a sanitary cover for milk containers and the like.

The object of my invention is to provide an inexpensive cover that will fit snugly 5 over the rim of a milk bottle.

A further object of my invention is to provide a cover having flexible features on the flange to expand sufficiently to pass over the larger portion of the rim of the neck, 10 and tension beneath the rim concealing that portion for sanitary purposes.

A still further object of my invention is to provide a cover for a milk bottle or the like that will function as a sealing means 15 without the assistance of the usual cap commonly used and such as illustrated in Fig. 1.

A still further object of my invention is to provide a cover that is water proof and will function in combination with the cap 20 sealing the bottle as a sanitary means.

These and other objects will hereinafter be more fully explained.

Referring to the drawings:

Fig. 1 is an elevation of a fragmentary 25 portion of a milk bottle, parts broken away for convenience of illustration.

Fig. 2 is a plan view of the cover as it appears from the flange side, the bottle being removed.

In the drawings, 1 is a top portion of a 30 milk bottle, preferably used to illustrate my invention, 2 is an ordinary cap such as commonly used for sealing the neck of the bottle, by which means the contents thereof 35 is retained, and the common practice among dairymen heretofore has been to deliver milk to the consumer without having any means to protect that portion of the neck that the milk will contact while being poured therefrom.

Bottles of milk thus delivered quite often 40 are placed on an outside step or the porch near the door, and the neck thus being exposed is subject to contamination from domestic animals or otherwise. To overcome this unsanitary condition I have provided a suitable cover 3 that will fit tightly over the top of the neck in such a way that it 45 will remain firmly intact until removed by the patron. The cover is preferably made of fiber having a flange conforming to the flare of the rim 4 of the bottle. The edge 50 of the flange is provided with a plurality

of corrugations; said corrugations being placed in groups along the peripheral edge 55 thereof the groups preferably placed at 120 degrees, the intervening portions of the flange being smooth, and adapted to fit snugly along the under curvature of the rim at which point the rim may be gripped 60 by the hand without expanding the flange as would be the case if the corrugations were flattened in gripping the rim of the bottle neck. The said corrugations terminating near the greater diameter of the curvature, 65 and being thus made it will allow the contracted edge of the flange to expand sufficiently to pass over the rim, and contract, causing the edge to fit snugly, the tendency of which is to pull the cap down tightly on 70 the mouth of the bottle.

It is now readily seen how that portion of the neck is concealed, that the milk will contact while being poured therefrom. Furthermore the covering will function as a sealing 75 means for the bottle when the cap 2 has been removed.

In view of the flexible construction of the flange and the waterproof means which is preferably of paraffine or like substance, the 85 cover can be used many times without deterioration, and also it may be sterilized.

I do not confine the use of the cover to milk bottles, as it may be applied to other containers for other substance that would 90 have a similar rim about the neck or mouth of the container.

Such other modifications may be employed as lie within the scope of the appended 95 claim.

Having thus described my invention, what I claim as new and desire to secure by Letters Patent is:

In a sanitary cover for milk containers a flanged cap constructed of paraffin sized 100 paper, a contraction of the peripheral edge of the flange by grouping at intervals a series of corrugations around the edge so that the peripheral edge will engage snugly to the under side of the bead of the neck 105 of the milk bottle, by which means thickening of the peripheral edge is eliminated and the edge adapted to yield when the cap is being placed or removed from the top of the bottle.

RALPH W. DEIMLER.
